DESIGN FOR A COMBINED CAN PUNCH AND BOTTLE OPENER

William H. Joyce, Hollis, N. Y.

Application June 25, 1947, Serial No. 139,897

Term of patent 14 years

(Cl. D22—2)

To all whom it may concern:

Be it known that I, William H. Joyce, a citizen of the United States, residing at Hollis, county of Queens, and State of New York, have invented a new, original, and ornamental Design for a Combined Can Punch and Bottle Opener, of which the following is specification, reference being had to the accompanying drawing, forming part thereof.

I claim:

The ornamental design for a combined can punch and bottle opener, as shown.

WILLIAM H. JOYCE.
